UNITED STATES PATENT OFFICE

LEONARD GRIFFITHS AND CECIL J. MORTON, OF COVENTRY, ENGLAND, ASSIGNEES TO
GENERAL ELECTRIC COMPANY, A CORPORATION OF NEW YORK

INDUCTION COIL

Application filed April 15, 1930, Serial No. 444,570, and in Great Britain November 29, 1929.

Our invention relates to induction coils such as used, for example, in ignition systems of internal combustion engines. Induction coils, as heretofore constructed, have ordinarily been made with a fixed core structure. If these induction coils are designed for obtaining the most satisfactory spark discharges for operation in an ignition system requiring a small number of spark discharges per minute such, of example, as a single cylinder engine, they do not produce the most satisfactory spark discharges when used on a higher speed engine, or a multi-cylinder engine, requiring a large number of sparks per minute. This is due to the fact that the time constant of the coil permissible to produce the most satisfactory spark discharge where a small number of sparks per minute are required is obtained by making the time constant of the windings of the coil large, and if the coil is used under conditions requiring a considerably larger number of sparks per minute, the time constant of the windings is not such as to produce the most satisfactory spark.

The object of our invention is to produce an induction coil in which the time constant of the windings is adjustable to adapt the coil for use in different ignition systems requiring a widely differing number of sparks per minute. We would accomplish this by providing an induction coil having primary and secondary windings which are arranged on a magnetic core extending through the windings and having a portion of the core adjustable about the windings to vary the time constant thereof.

Our invention will be more fully set forth in the following description referring to the accompanying drawing, and the features of novelty which characterize our invention will be pointed out with particularity in the claims annexed to and forming a part of this specification.

In the drawings Fig. 1 is a longitudinal section of an induction coil embodying our invention, and Fig. 2 is a section on the line 2-2 of Fig. 1.

Referring to the drawings, the induction coil, which we have illustrated as an exam-

ple of one manner of carrying out our invention, includes the soft iron-wire core 10 having a primary winding 11 wound thereon between an insulating sleeve 12 closely fitting the core 10 and terminating a short distance from the ends thereof and an insulating sleeve 13 surrounding the primary winding 11 and extending the entire length of the core 10. The secondary windings 14 and 15 of the coil are arranged on the sleeve 13. 55 These secondary windings are retained in place by insulating sleeves 16 and 17 which are separated by an insulating spacing ring 18 arranged on the sleeve 13. The primary and secondary windings of the induction coil are secured within a cylindrical insulating casing 19 by end-caps 20 and 21 of molded insulating material which are fitted on the sleeve 13 and inside of the cylindrical casing 19, the entire structure being secured 60 together by a bolt 22 extending through the core 10 and the end-caps. The secondary windings 14 and 15 of the induction coil are connected in series between terminals 23 which are molded in the end-caps. 65 Laminated magnetic segments 24 extend from the ends of the core 10 to the cylindrical casing 19 and are preferably retained in place by molding them in the insulating end-caps 20 and 21. It will be observed that the core 10 70 of iron wires and the laminated magnetic segments 24 constitute a U-shaped core structure within the casing 19 in which the primary and secondary windings of the induction coil are arranged between the arms 75 of the U.

In order to vary the time constant of the windings of the induction coil, that is to say, the ratio of the inductance to the resistance of the windings, we arrange a laminated magnetic core member 25 across the magnetic segments 24 to complete the magnetic circuit including the core 10, magnetic segments 24 and magnetic core member 25 80 so as to vary the reluctance of the flux path 85 through the core structure of the induction coil. We prefer to adjustably secure the core member 25 to the casing 19 by clamping bands 26 which extend about the casing and are bolted to the core member as indicated 90 95 100

- at 27. The induction coil may be supported in any convenient manner, but we prefer to support the same on feet 28 which are bolted to the magnetic member 25 at 29. 5 By this arrangement, upon loosening the bolts 27 we can move the casing 19 and end-caps 21 with respect to the magnetic core member 25 so as to vary the air gap between the segments 24 and the core member, which is greatest when the casing 19 and the end-caps 20 and 21 are turned to bring the magnetic segments into the position indicated at 24' in Fig. 2, which is the farthest from the magnetic core member. 10
- 15 When our induction coil is to be used in an ignition system requiring a small number of sparks per minute we adjust the casing 19 in the end-caps 20 and 21 so as to bring the magnetic segments 24 into alinement with the magnetic core structure 25, as shown in full lines in Fig. 2. This gives a maximum time constant for the windings of the induction coil and gives the most satisfactory spark under those conditions. 20
- 25 When the induction coil is used in an ignition system where the greater number of spark discharges per minute are required, the time constant of the induction coil is adjusted to a lower value, and this can readily be accomplished by loosening the bolts 27 and turning the casing 26 and the end-caps 20 and 21 so as to move the magnetic segments 24 out of alinement with the magnetic core member 25 and increase the air 30 gap between them. In this adjusted position the coil will operate more satisfactorily when it is required to supply a higher number of spark discharges per minute. 35
- Modifications of the structure which we have described will occur to those skilled in the art so that we do not desire our invention to be limited thereto, and we intend in the appended claims to cover all modifications which do not depart from the spirit 40 and scope of our invention. 45
- What we claim as new and desire to secure by Letters Patent of the United States is:
1. An induction coil having a U-shaped magnetic core, primary and secondary windings arranged between the arms of said U-shaped core, and a magnetic core member extending across the arms of said U-shaped core and adjustable about the axis 50 of said windings to vary the time constant thereof. 55
  2. An induction coil having a core, primary and secondary windings arranged about said core, a casing enclosing said core and said windings, and means including a magnetic core member secured to said casing and adjustable with respect thereto for varying the time constant of said windings. 60
  3. An induction coil having a core, primary and secondary windings arranged on 65
- said core, a casing surrounding said core and said windings, magnetic segments extending outwardly from said core, end-caps secured to said casing for retaining said segments in place, and means including a magnetic core member secured to said casing and adjustable with respect to said segments for varying the time constant of said windings. 70
4. An induction coil having a core, primary and secondary windings arranged on 75 said core, a cylindrical casing surrounding said core and said windings, end-caps secured to said casing having magnetic segments attached thereto, and a magnetic core member secured to the outside of said casing 80 and adjustable with respect to said segments for varying the time constant of said windings. 85
- In witness whereof, we have hereunto set our hands this twenty-sixth day of March, 1930.
